UNITED STATES PATENT OFFICE.

ALBERT W. WINSHIP, OF UTICA, NEW YORK.

WARDROBE-TRUNK.

1,096,979.

Specification of Letters Patent. Patented May 19, 1914.

Original application filed October 26, 1911, Serial No. 656,883. Divided and this application filed February 10, 1912. Serial No. 676,780.

To all whom it may concern:

Be it known that I, ALBERT W. WINSHIP, of Utica, in the county of Oneida and State of New York, have invented certain new and useful Improvements in Wardrobe-Trunks; and I do hereby declare that the following is a full, clear, and exact description thereof, which will enable others skilled in the art to which it appertains to make and use the same, reference being had to the accompanying drawings, and to the reference-numerals marked thereon, which form part of this specification.

The subject matter of this invention was originally a part of a former application filed by me October 26, 1911 as Serial No. 656,883.

My present invention relates to display racks particularly adapted to wardrobe trunks and to the form of wardrobe trunks particularly adapted to give most convenient access to said rack.

One object of my invention is to provide in a wardrobe-trunk an improved system of slideways of great simplicity, convenience and effectiveness.

Another object is to provide an improved, simple way of securing the clothes-retaining rack on the slideways in desired position.

A further object is to supply proper means for preventing the clothes-retaining rack or the clothes-hangers from accidentally slipping off from the slideways and at the same time permit their ready removal from said slideways when desired.

In the drawings I have shown my invention embodied in a wardrobe-trunk which is combined with a chiffonnier compartment in the same main trunk as this is a common and convenient arrangement. It will be evident, however, that the chiffonnier compartment is not in any way necessary to any feature of my invention.

In the drawings and in the specification hereafter I have shown and described my invention as applied to a wardrobe-trunk having one entire upright side open and the entire top also open and having the side opening of the wardrobe compartment provided with a single closure hinged adjacent to one upright side and the top closed with a single closure hinged along the back upper side of the wardrobe compartment. This arrangement is my preferred form as it ob-

viously gives the easiest and fullest access to the compartment and renders the system of slideways and racks most convenient in use. It will be evident, however, that the closures can be mounted upon the body of the trunk in other ways or could be made so as to be entirely detached. I further prefer that the top of the compartment be open as herein shown but it will be noted that the wardrobe compartment could be formed without opening at the top and still allow the extension slideways to be moved as hereinafter shown and allow the clothes-retaining rack and clothes-hangers to be moved back and forth thereupon. The open top, however, is much preferable as it gives much fuller access to the compartment and allows practically double the space for inspection or display of the different garments and particularly for the removal of garments from the back of the compartment upwardly without lifting from the slideways those that are at the front.

Figure 1 is a perspective view of an opened trunk embodying my invention. Fig. 2 is a horizontal sectional view across the trunk just below the top and top closure. Fig. 3 is a perpendicular sectional view on line 3—3 of Fig. 2 on an enlarged scale. Fig. 4 is a perpendicular sectional view on line 4—4 of Fig. 3. Fig. 5 is a side elevation on a similarly enlarged scale of the joint between one of the fixed slideways and its extension.

Referring to the drawings in a more particular description the trunk casing consists of a bottom 9 to which are secured two whole sides 10 and 11 adjacent to each other and an internal partition 12 parallel to side 11 and secured to side 10 and dividing the trunk perpendicularly into two compartments, 13 and 14 which I will respectively designate the wardrobe compartment to the left as seen in Fig. 1 and the chiffonnier compartment to the right as seen in Fig. 1. Further fixed parts of the trunk are a half-side 15 rising from the bottom 9 and secured to the near side edge of the partition 12 as seen in Fig. 1 and a half-top 16 secured to the top edges of the side 11, the partition 12 and the portion of the side 10 between the partition 12 and the side 11. It will be seen that this construction leaves the broad outer side and the top of the wardrobe compartment en-

tirely open and also one narrow side of the chiffonnier compartment open. For the latter opening there is provided a closure 17 perpendicularly hinged to the half side 15 along the line of its contact with the adjacent edge 5 of the internal partition 12.

To close the side opening of the wardrobe compartment 13 there is provided a closure 24 perpendicularly hinged to the side 10 and 10 having on each side edge valance strips 25 and 26 projecting at right angles from said closure edges to overlap the edges of the sides 10 and 15 respectively. From the lower edge of this closure projects downward a 15 valance strip 27 to overlap the outside of the bottom at 28 which here extends upward for that purpose and far enough so that the bottom of the closure with its downwardly extending valance strip will swing clear of the 20 floor as it is opened.

To close the top opening of the wardrobe section, there is provided a closure 29 horizontally hinged to the half-top 16 along the line of its contact with the upper edge of 25 the partition 12. From the free edges of this closure there project at right angles thereto valance strips 30, 31 and 32 to overlap the upper edges respectively of the side 10, side 15 and side closure 24.

30 Spring catches 22 secure the free side edge of the closure 24 to the side 15 and the edge of the top closure to the overlapped top edge of the side closure 24. A lock 33 having its two members upon the adjacent edges of the 35 top closure 29 and side closure 24 provides means for locking the wardrobe section.

The chiffonnier compartment may be provided with drawers or other containers 34 which may be readily withdrawn therefrom 40 through the side opening therein.

Around the inside of the wardrobe compartment extends a U-shaped metal strip 35 having its loop portion fastened to the partition 12 and its ends extended nearly to the 45 front edges of the sides 10 and 15 and securely fastened thereto. This strip further strengthens the upper forward corners of the sides 10 and 15 and its loop portion affords a secure anchorage for the bent inner 50 ends 36 of a pair of slideways 37 horizontally arranged and spaced a short distance from either side of the wardrobe compartment and extending to the front or open side thereof. Just back from the outer end 55 of each of these slideways 37 there is rigidly fastened a brace 38 which extends downwardly and outwardly in a diagonal direction to the adjacent side of the compartment to which it is rigidly secured. To the free 60 end of each of these slideways is perpendicularly hinged an extension slideway 39 by means of a deeply interlocking rule joint formed from intermeshing projections 37^a and 39^a formed integral with the slideway 65 37 and the extension slideway 39, through

which projections a joint pin 40 is inserted. The joint is adapted to stop the extension when it has been swung straight out into line with the fixed slideway as shown in Figs. 2 and 3 and to allow the extension to 70 be swung around horizontally to a position entirely within the wardrobe compartment as indicated in dotted lines in Fig. 2 and allow the side closure thereof to be closed. Over these slideways fit and slide notched 75 crosspieces 41 to which are secured clothes-hangers 42 of any desired form allowing the clothes to be drawn out from the wardrobe compartment and be suspended upon the extension slideways without the wardrobe 80 compartment and where they can be easily seen or removed.

Upon the slideways is slidingly mounted a clothes-retaining rack formed of uprights 43 and cross-pieces 44 and sliding clutches 85 45 adapted to allow the rack to be slid back and forth upon the slideways 37 and 39 and to hold the rack in any position on said slideways without any further operation. The clutch 45 is of metal and has strap portions 46 for securing it firmly to the uprights 43 of the rack and in its body portion has an opening 47 of the shape and substantially the size of the slideways in cross-section and so that the clutch encircles the 95 slideway on its upper and inner side entirely and partly on the outer and lower side as plainly seen in Fig. 3. This arrangement prevents the rack from being removed from the slideways in any way except from the outer ends thereof. The outer ends of the extension slideways are turned upwardly in the shape of hooks 48 which prevent the rack from slipping off of the slideways when pulled out in the ordinary way but allow the 100 rack to be removed by moving its lower end outwardly and upwardly so as to let the clutch ride around the upward curve of the hook 48.

The opening 47 in the clutch 45 is disposed at a little less than a right angle to the general plane of the rack and slopes downwardly toward the inner side of the opening as plainly seen in Fig. 4 resulting in 110 points 49 on the inner upper side of the opening and 50 on the outer lower side of the opening coming into contact with the slideways as the rack drops toward the perpendicular from its own weight or is held 115 that way from the pressure of the clothes which tends to shove its lower end outwardly. It is obvious that as these points 49 and 50 are so brought into sharp contact with the slideways, they prevent the rack from being slid outwardly upon the slideways but will allow it to be moved either way upon the lower end of the rack being pushed inwardly far enough to reduce the angle between the rack and slideways 120 and so take the points 50 of the clutch out of 125 130

holding engagement with the slideways. As the clutch 45 does not encircle the outer portion of the bottom of the slideways nor the lower part of its outer sides it slides freely 5 by the brace 38.

In operation the wardrobe closures 24 and 29 are opened, the extension slideways swung out into extended position and clothes-retaining rack moved out onto the 10 extension slideways by first pressing inwardly upon the lower part of the rack. The rack may be then entirely removed from the slideways as heretofore described and the clothes-hangers slid off of the ends of 15 the extensions and the clothes-hangers slid out part way and then lifted up taking the clothes up between the extension.

What I claim as new and desire to secure by Letters Patent is:

20 1. In a wardrobe compartment, horizontally fixed slideways spaced from the sides of said compartment and secured thereto at the rear, extensions perpendicularly hinged directly to the outer ends of said fixed slide- 25 ways and adapted to be swung horizontally in line therewith and supported solely thereby and to be turned back horizontally within said compartment, a clothes-retaining rack, clutches supporting said rack and 30 partly encircling all sides of said slideways and adapted to slide thereupon, braces connecting said slideways near their forward ends to the adjacent sides of the compartment

ment and adapted to allow the said clutches to be moved therepast. 35

2. In a wardrobe compartment, horizontally fixed slideways spaced from the sides of said compartment and secured thereto at the rear, extensions perpendicularly hinged directly to the outer ends of said fixed slide- 40 ways and adapted to be swung horizontally in line therewith and supported solely thereby and to be turned back horizontally within said compartment, a clothes-retaining rack, clutches supporting said rack and 45 partly encircling all sides of said slideways and adapted to slide thereupon, braces connecting said slideways near their forward ends to the adjacent sides of the compartment and adapted to allow the said clutches to be 50 moved therepast, the opening in said clutches slanting downwardly toward the inner side of the rack and adapted to make said clutches grip the slideways as the lower end of said rack is pressed outwardly toward a perpendicular position and allowing said clutches 55 to slide freely upon said slideways by moving the lower end of said rack inwardly.

In witness whereof I have affixed my signature, in the presence of two witnesses, this 60 31st day of January 1912.

ALBERT W. WINSHIP.
